UNITED STATES PATENT OFFICE.

EDWARD C. BROADWELL, OF CHICAGO, ILLINOIS, ASSIGNOR TO J. W. MEAKER, JR., OF CHICAGO, ILLINOIS.

SOLVENT FOR METALS.

No. 884,705.

Specification of Letters Patent.

Patented April 14, 1908.

Application filed February 28, 1906. Serial No. 303,516.

To all whom it may concern.

Be it known that I, EDWARD C. BROADWELL, a citizen of the United States, and a resident of Chicago, county of Cook, and 5 State of Illinois, have invented certain new and useful Improvements in Solvents for Metals; and I do hereby declare that the following is a full, clear, and exact description of the same.

10 This invention relates to a solvent for metals and more particularly to a solvent adapted to be used in the process of refining and treating ores to extract the metals therefrom.

15 Heretofore all solvents utilized for the treatment of ores and refining of metals have been more or less objectionable for the reason that should the metal or a major portion of the metals in solution have a higher solution

20 tension than lead or copper, then a large portion of the wattage used to deposit such metal or metals at the higher potential would waste in hydrogen evolution, especially with an insoluble anode. In other

25 words previous acid solvents have formed highly dissociated electrolytes. In the sulfonic acid salts of metals having a solution tension similar to the metals of the earth group this defect is not inherent, and yet,

30 withal, the sulfonic acid (say phenolsulfonic acid) is more energetic a solvent than would be oxalic or acetic.

The object of the invention is to provide a chemically avid metal solvent which, owing 35 to its great affinity for the metals, acts to readily take them into solution from which they may be separated by electrolysis and which will form an electrolyte from which the metals may be deposited without such 40 loss of wattage in hydrogen evolution and which will at the same time form a very active solvent.

The invention consists in the matters hereinafter described and more fully pointed out 45 and defined in the appended claims.

The solvent consists of the sulfonic acids of the carbocyclic hydrocarbons, or of the carbocyclic oxy-compounds, such as the phenols, aldehydes and carboxylic acids.

50 As a carbon-hydrogen nucleus I prefer benzol or phenol as giving very soluble and chemically avid sulfonic acids, although naphthalene, anthracene, phenanthrene, chrysene and similar hydrocarbon compounds, as 55 found in gas tar and pitch may be utilized

as hydrocarbons to which may be attached the sulfonic group or groups.

Where an oxidizing influence in conjunction with a strong chemical combining power is needed, as in the dissolution of the noble 60 metals, gold, silver and those inclusive of and grouped with platinum, a mono or even a poly-nitro-sulfonic acid is used, to a strong solution of which a small quantity of haloid salt is added, such as common salt, in which 65 latter case the oxygen derived from the nitro group in its reduction to an amido-group, combines with the metal of the haloid salt (sodium when sodium chlorid is used) thus giving potentially incipient chlorin in a 70 pseudonascent state, which dissolves the noble metal, or metals, while the sodium oxid thus formed, after its immediate conversion to hydroxid by the water present, is neutralized by a small portion of the sulfonic 75 acid used, forming a sodium nitro-sulfonate of the carbo-cyclic series, or a sodic nitro-haloidal-sulfonate of this series, or a sodic nitro-amido-sulfonate, or even a sodic nitro-haloidal-amido-sulfonate of said series, ac- 80 cording to the nature of the sulfonic acid used as being best suited for a particular ore, or the proper mechanical properties requisite in an electro-deposit of the metal or alloy to be obtained in refining or for the recovery of 85 the metals from the lixivium from ore treatment. Should pitch or tar be used as a foundation material for sulfonation, I find it best to add two or more sulfonic groups in order to attain fair solubility in water. For 90 reguline deposits of such metals as bismuth and antimony, which tend to the formation of dendritic crystals and treeing the haloidal-sulfonic acids may be used.

Obviously the particular composition will 95 depend to a great extent upon the character of the metal or metals being treated and I therefore do not desire to be limited in this application other than as necessitated by the prior art and as stated in the claims.

100 I claim as my invention:

A metal solvent comprising a mono-nitro-sulfonic acid and a suitable haloid salt.

In testimony whereof I have hereunto subscribed my name in the presence of two sub- 105 scribing witnesses.

EDWARD C. BROADWELL.

Witnesses:

W. W. WITHENBURY,
WM. C. SMITH.
